UNITED STATES PATENT OFFICE.

MICHAEL LYONS, OF WORCESTER, MASSACHUSETTS.

DOOR-FASTENING DEVICE.

Application filed February 17, 1925. Serial No. 9,874.

To all whom it may concern:

Be it known that I, MICHAEL LYONS, a citizen of the United States, residing at Worcester, in the county of Worcester and State of Massachusetts, have invented a new and useful Door-Fastening Device, of which the following is a specification.

This invention relates to a fastening device for double doors, the device being particularly adapted for use on the doors of barns, garages, sheds, and other similar structures.

It is the object of my invention to provide a fastening device so designed that two doors or other similar parts may be securely fastened thereby, and that they may be held firmly in a single plane when thus secured.

Another object is to provide a door fastening device in which there are no loose parts to become mislaid or lost.

To the attainment of this object, I have provided a door fastening device in which a fastening bar has both a sliding and a swinging movement, and in which these movements must follow each other in a predetermined order.

My invention further relates to arrangements and combinations of parts which will be hereinafter described and more particularly pointed out in the appended claims.

A preferred form of the invention is shown in the drawings, in which

Fig. 1 is a plan view of my improved fastening device;

Fig. 2 is a front elevation thereof;

Figs. 3, 4 and 5 are views similar to Fig. 2, but showing the parts in successive positions;

Fig. 6 is an end elevation, looking in the direction of the arrow 6 in Fig. 3; and

Fig. 7 is a plan view similar to Fig. 1, but showing a slight modification.

Referring to Figs. 1 to 6, I have shown my improved fastening device as applied to a pair of double doors A and B. A pivot plate 10 is secured to the door A and is provided with a stud 11 having a washer 12 at its outer end. A fastening bar 13 is provided with a slot 14 to receive the stud 11 and is thus mounted on the door A for both sliding and swinging movement on the stud 11.

One end of the bar 13 is reversely bent to form a hook-like portion 15 which is adapted to engage a keeper 16. This keeper is

also mounted on the door A and has a portion 17 spaced from the body portion of the keeper and provided at its lower end with an enlarged end portion 18.

The hook-shaped portion 15 of the bar 13 is adapted to embrace the portion 17 of the keeper 16 but will not pass over the enlarged end portion 18.

A second keeper 20 is mounted upon the door B and is provided with a portion 21 bent outward and spaced from the main part of the keeper providing an open-ended recess to receive the bar 13 when it is swung downward about its pivot 11.

A hasp 22 is pivoted to the end of the bar 13 and engages a staple or other securing device 23, fixed to the door B. A padlock 24 or any other usual or convenient fastening may be provided to hold the hasp 22 and fastening 23 together.

The method of operating my improved door fastening device is clearly indicated in Figs. 2 to 5 inclusive. In Fig. 2, the doors are shown as securely locked, the bar 13 being seated in the keepers 16 and 20, and being held from swinging movement by the keeper 16, and from sliding movement by the fastening device 23.

In the operation of unlocking the doors, the pad-lock 24 is first removed, and the hasp 22 is swung forward as indicated in Fig. 3. The bar 13 is then pushed endwise as indicated in Fig. 4 until the hook-shaped end 15 of the bar clears the keeper 16. The bar 13 is then swung upon its pivot stud 11, out of the keepers 16 and 20 to the inoperative position shown in Fig. 5. In locking the doors, the operations above described are performed in the reverse order.

In Fig. 7, I have shown a slight modification, in which the hasp 30 is pivoted to the opposite end of the bar 31 and in which the fastening device 32 is secured to the door A instead of to the door B. In this case the hooked portion 33 of the bar 31 may be conveniently formed as a separate plate riveted thereto.

Having thus described my invention and the operation thereof, the advantages of the invention will be readily apparent. When the parts are in the position shown in Fig. 2 the bar is firmly seated in the keepers 16 and 20 and holds the doors firmly in a single plane, from which they can be moved only by breakage of parts, unless the lock is removed and the hasp is swung upward.

to permit sliding movement of the bar. The parts are easily and simply made and are readily attached to the doors, without cutting the doors or performing other preliminary operations thereon.

Having thus described my invention and the advantages thereof, I do not wish to be limited to the details herein disclosed otherwise than as set forth in the claims.

10. What I claim is:—

1. A door fastening device comprising a pivot plate, a bar having a sliding and swinging connection to said plate, a hasp pivoted at one end of said bar, a securing device for said hasp, a keeper engaging said bar between said hasp and pivot plate, and a second keeper engaging the end of said bar remote from said hasp, said bar being held from any swinging or transverse movement in any portion thereof relative to said second keeper or to said pivot plate after said bar is moved longitudinally to position relative to said second keeper and is operatively engaged thereby.

2. A fastening device for double doors comprising a pivot plate and a keeper secured to one door, a second keeper and a securing device mounted on the other door, a bar having a sliding and swinging motion relative to said pivot plate and adapted to engage said keepers, and a hasp on said bar engaging said securing device, said bar being held from all swinging or angular movements by said pivot plate and by one of said keepers after said bar has been moved longitudinally to latching position.

3. A fastening device for double doors comprising a pivot plate, a bar having sliding and pivotal connection to said pivot

plate, a keeper on each door, said keepers having open-ended recesses to receive said bar and said recesses being oppositely disposed, one of said keepers having an enlarged end portion cooperating with a hooked portion of said bar to prevent swinging movement of said bar when engaged thereby, and means to hold said bar from sliding movement when thus engaged by said keeper.

4. A fastening device for double doors comprising a pivot plate, a bar having sliding and pivotal connection to said pivot plate, a keeper on each door, said keepers having open-ended recesses to receive said bar and said recesses being oppositely disposed, one of said keepers having an enlarged end portion cooperating with a hooked portion of said bar to prevent swinging movement of said bar when engaged thereby, a hasp pivoted to said bar, and a securing device on one of said doors for said hasp.

5. A fastening device for double doors comprising a pivot plate and a keeper secured to one door, said keeper having a portion spaced outward and provided with an enlarged end portion, a bar having a sliding and swinging connection to said pivot plate and having a hooked end to engage said keeper within said enlarged portion, a second keeper fixed on the other door and having an open-ended recess to receive said bar, a hasp pivoted to an end of said bar, and a securing device for said hasp.

In testimony whereof I have hereunto affixed my signature.

MICHAEL LYONS.
